UNITED STATES PATENT OFFICE

EDWIN RUUD, OF PITTSBURGH, PENNSYLVANIA

VALVE

Application filed March 25, 1926. Serial No. 97,256.

This invention relates to valves and more particularly to those of the automatic cut off type such as are commonly employed in connection with various kinds of heaters as, for example, automatic water heaters.

A valve of this type, as generally constructed, is provided with a thermally controlled mechanism which normally maintains the valve open to permit passage of gas or other fuel to a connected burner but which, if an associated pilot light should be extinguished from any cause, will be moved as a result of the reduction in temperature to a position permitting the valve to close. In reopening the valve, upon relighting the pilot light, the valve must then be held in open position until the thermally controlled mechanism is heated sufficiently by the pilot flame to be moved into position to itself hold the valve open.

20 An object of this invention is to provide a valve of the type set forth of such construction and arrangement that when opened to permit fuel to flow to an associated burner or the like it will automatically remain open until the associated pilot flame is extinguished from any cause.

25 A further object is to provide a device of the type set forth which will be simple in construction, positive and reliable in operation and easy to manufacture and assemble.

These and other objects which will be apparent to those skilled in this particular art are accomplished by means of this invention, one embodiment of which is illustrated in the 30 accompanying drawings, in which Figure 1 is a vertical sectional view through one form of gas valve and associated burner constructed in accordance with one embodiment of this invention.

40 Fig. 2 is a somewhat fragmentary vertical sectional view of the embodiment shown in Fig. 1 when the valve has been moved to its "initial open" position. Fig. 3 is a view similar to Fig. 2, but showing the relation of 45 elements when the valve has been moved to its "final or ordinary open" position.

The particular embodiment of this invention which has been chosen for the purposes of illustration includes a valve 5 which is normally pressed by a valve spring 6 against

the valve seat 7 to close the valve opening. A valve stem 8 is associated with the valve for guiding its movement and extends outwardly through the valve housing 9 on each side thereof. One projecting end is provided with 55 a head 10 by means of which the valve can be manually opened against the pressure of the valve spring to permit gas or other fuel to flow through the inlet 11, connecting pipe 12 and to an associated main burner such, for example, as the burner 13', being the usual form of burner found in automatic water heaters. The usual pilot light or burner 13 is provided in connection with the main burner 13' and gas is supplied to the pilot light 60 through the well-known separate supply pipe 13''. The opposite end of the valve stem from the head 10 is received within a housing 14 enclosing an upper lever 15 pivoted upon a supporting rod 16 or the like. 65 A spring 17 is associated with the end or stop portion of the lever adjacent the valve stem so as to press the same toward the stem and the pressure of the spring can be varied by an adjusting screw 18 forming an abutment 70 for the adjacent end of the spring and adapted to be locked by any suitable means, such as a lock nut 19. A shoulder 20 is formed on the end of the lever to prevent the same from being forced past the end of the valve stem. 75

80 A thermal element 21 is associated with the burner or pilot light 13 so as to receive heat from the flame thereof and is adjustably connected to an operating rod 22 by any suitable means, such as adjusting nuts 23. The rod 85 extends into the housing 14 and bears against a lever operating device, such as the lug 24, so that cooling of the thermal element as a result of the extinction of the pilot flame moves the operating rod to the left, as illustrated in the drawings, and forces the lever 15 away from the end of the valve stem against the pressure of the spring 17. When the valve rod engaging face 15' (see Figure 2) of the lever is so moved it will be apparent that the 90 valve spring 6 will close the valve to cut off the supply of fuel to the main burner 13'. In this way the supply of fuel to the main burner is automatically cut off upon extinguishing the pilot burner flame, and the flow of a large 95 100

quantity of unburned fuel through the main burner is prevented.

In reopening the valve, so as to permit gas to flow to the main burner, as is desirable when my invention is employed with a water heater and water is flowing through the heater, as will be readily understood by those skilled in the art, it is necessary to manually pull the valve stem head 10 outwardly and in order to overcome the disadvantage heretofore present in such devices, namely, the necessity for holding the valve open until the heat from the relighted pilot burner has raised the temperature of the thermal or temperature sensitive element sufficiently to move the operating rod 22 to the right far enough to permit the lever 15 to be again in position to engage the end of the valve stem and hold the valve open, there is provided a suitable mechanism for performing the function until the thermal or temperature sensitive element has been heated sufficiently for the lever 15 to operate.

As illustrated, this mechanism includes an arm or upper lever 25 which may conveniently be pivoted on the pivot shaft 16. The arm or lever is provided with the valve stem engaging face 26 at the end thereof which is located beyond the rod engaging face 15' of the lever 15 and a coil spring 27 is associated with the arm 25 so as to normally press the valve stem engaging face toward the valve stem. The arm is also provided with an extension or abutment 28 which extends toward the adjacent portion of the lever 15.

It will be apparent that when the pilot flame has been extinguished from any cause the valve 5 will be closed so as to cut off the flow of gas to the main burners, thus preventing any possible escape of a large quantity of unburned gas, and the elements will then be in the position indicated in Fig. 1. When the pilot light is relighted, to permit the flow of gas to the main burners, the head 10 is pulled outwardly to open the valve. Such opening of the valve has moved the opposite end of the valve stem within the housing 14 so as to permit the arm 25 to be moved into the position indicated in Fig. 2 whereupon the adjacent end or stop portion of the valve stem is engaged by the valve stem engaging face 26 of the arm and the valve is held open against the pressure of the spring 6. The engagement of the longest downwardly extending leg or abutment 28 of the upper stop 26a with the adjacent face of the lever 15 properly positions the arm with relation to the valve stem and prevents the former moving past the latter under the influence of the spring 27. The thermal element being cool at this time the rod 22 prevents movement of the lever 15 under the impulse of its associated spring 17. Heat from the pilot flame will raise the temperature of the thermal element which, in response to such change in tem-

perature, will move the rod 22 to the right. Such movement permits the spring 17 to move the lever 15 upwardly as illustrated in the drawings. Inasmuch as the lever spring 17 is stronger than the spring 27 associated with the arm, the latter will be moved away from the end of the valve stem until the stem snaps off the engaging face 26 of the arm 25 and on to the valve stem engaging face 15' of the lever 15, see Fig. 3. The shoulder 20 on the lever 15 prevents further movement thereof and the valve is thus maintained open as long as the pilot burner is lighted. When the burner is extinguished from any cause the thermal element forces the lever 15 downwardly against the pressure of the spring 17 and the valve stem will snap off the edge of the supporting face 15' and permit closing of the valve as illustrated in Fig. 1. In view of the fact that the face 26 of the arm 25 is positioned beyond the face 15' of the lever, it will be apparent that downward movement of the lever 15 as a result of cooling of the thermal element prevents the arm 25 from being moved into position at the end of the valve stem as the end of the arm 25 will merely contact with the side of the valve stem and slide therealong, see Figs. 1 and 3.

It will be apparent that the present invention provides a safeguard against the danger resulting from the emission of relatively large quantities of unburned gas through the main burners when the pilot light has been extinguished from any cause, and that the heater can be rendered operative merely by lighting the pilot light and pulling the valve 5 to open position, where it is automatically held even before the thermostatic mechanism has become operative.

Figure 2 shows the relative positioning of certain parts of my operating mechanism immediately after the valve stem head 10 (which is employed as a resetting means) has been pulled out against the tension of the associated spiral spring 6; that is, after the valve 5 has been initially changed from a "closed" position (see Figure 1) to an "open" position (see Figure 2). As the stem 8 is pulled back, the spiral tension spring 27 pushes an associated upper stop member 26a downward as soon as the stem engaging face 26 clears an inwardly extending end 8a of the valve rod or stem 8. Then, as the manual (or it may be, of course, mechanical) pull upon the head 10 of the stem 8 is released, the spring 6 snaps it back, in order that the face of the inwardly extending end 8a will tightly and resiliently abut against the stem engaging face 26 of the stop 26a and initially hold the valve 5 open.

The lower position of the upper stop 26a is limited by the pressing of its lowermost abutment 28 against the upper face or platform of the extending stop end of the lever 15. At this time the operating rod 22 is dis-

posed to the left since the thermal unit is cool; but, after the pilot light 13 has been burning for a given period of time, the thermal unit 21 (see Figure 1) tends to pull the rod 22 to the right, thereby releasing its pressure upon the lug 24 of the lever 15. Thence, the spiral spring 17 associated with and upwardly pressing the bottom face of the extending end of the lever 15 is permitted to raise the stop 10 end of this lever and raise the upper stop 28 against the relatively lesser tensile force exerted by the smaller spring 27. As a result, the end '8a of the valve stem slides off the front face 26 of the stop 26a and slips against 15 the front face 15' of the lever 15, in order that the final position shown in Figure 3 may be attained.

Although I have described what I now consider the preferred embodiment of this invention it will be apparent that various changes, additions, substitutions and omissions can be made in the details thereof without departing from the spirit of this invention or the scope of the appended claims.

25 What I claim as new and desire to secure by Letters Patent is:

1. The combination with a main gas burner of a valve for controlling the flow of gas thereto, a valve stem, a movable stop adapted 30 to cooperate with said valve stem to hold said valve in open position to permit said burner to be lighted, a pilot burner and thermally responsive mechanism associated with said pilot burner and operative upon lighting of 35 said pilot burner to displace said stop in holding said valve open.

2. The combination with a main burner for an automatic water heater, of a cutoff valve for controlling the flow of fuel thereto, a 40 pilot light, means normally biased to hold said valve in open position in response to movement of the valve to said position and thermally actuated mechanism actuated in response to the heat of said pilot light for 45 displacing said means in holding said valve open as long as said pilot light burns.

3. In combination, a valve having a valve stem disposed for longitudinal movement, means biasing said valve towards a close 50 position, two members having adjacent ends pivotally supported, means biasing the opposite ends of said members towards engagement, said ends when in engagement being disposed to act as a stop for said valve stem 55 when the valve is open, thereby holding said valve open, and thermally responsive means disposed to separate said engaging ends to permit the end of said stem to pass therethrough when separated whereby the valve is 60 released to its closed position.

4. In a valve controlling mechanism, in combination, a valve normally biased to a closed position, said valve being provided with a valve stem, two stops disposed adjacent one end of said valve stem and biased

towards engagement, one of said stops being disposed to engage the adjacent end of said stem in response to the movement of the valve to its full open position and the other of said stops being offset with respect to the end of the stem to permit a partial closing of the valve, and thermally responsive means for actuating said offset stop to effect separation of the stops, thereby permitting the end of the stem to pass therebetween and rendering said valve biasing means effective to close the valve. 70 75

5. Controlling mechanism for a valve having a stem for actuating the valve, said valve being normally biased towards a closed position, said mechanism comprising a plurality of movable stops adjacent one end of said stem, means normally biasing said stops towards engagement, and thermally responsive means for actuating one of said stops to effect separation thereof thereby permitting the end of the stem adjacent to the stops to pass therebetween and the valve to close, one of said stops, when the valve is open, being disposed to engage the end of the valve stem. 80 85 90

6. The combination with a valve having a rodlike longitudinally extending stem and an associated gas burner, of a pivoted arm movably positioned adjacent the end of the valve stem, a spring for moving said arm into abutting relation with the end of said valve stem upon opening of said valve for maintaining said valve in open position and permitting the flow of fuel to the associated burner, a spring-pressed lever adapted to control the position of said arm, temperature sensitive mechanism for operating said arm when subjected to a predetermined temperature, and a lug on said lever for controlling the relative positions of said lever and said arm. 100 105

7. The combination with a poppet valve having a stem and an associated burner, of a pivoted arm normally engaging the side of the valve stem near one end thereof, a spring for moving said arm into abutting relation with the end face of said stem upon opening of said valve, so that said valve will be held in such open position for permitting fuel flow to the associated burner, a spring-pressed lever adapted to control said arm, and a temperature sensitive means for operating said lever when subjected to a predetermined temperature. 110 115

8. The combination with a gas burner, of a poppet valve for controlling the flow of gas thereto, a usual form of longitudinal valve stem therefor, a pivotal arm having a movable end positioned adjacent the end of said valve stem, resilient means for moving said arm into engagement with the end of said stem upon opening of said valve for maintaining said valve in open position and for permitting a flow of gas to the burner, a resiliently disposed member for displacing said arm and for maintaining said valve in 120 125 130

a final open position, and thermally actuated means for controlling the displacement of said member.

9. The combination with a fluid burner of a longitudinal stem valve for controlling the flow of fluid thereto, upper and lower lever members pivoted at a common point and disposed adjacent the end of said valve stem, means normally holding said members in

10 abutting relationship with respect to each other adjacent the end of said valve stem, one of said levers abutting against the end of said valve stem, and additional means for modifying the action of said first mentioned

15 means and displacing one of said levers from abutting relation with respect to the end of the valve stem and placing the other lever in abutting relationship therewith, said additional means including a pilot burner, and a

20 temperature responsive mechanism associated with said pilot burner and operative upon the lighting of said burner for changing the relative position of said levers with respect to said valve stem.

25 10. The combination with a fluid burner of a valve for controlling the flow of fluid thereto, a valve stem, a pilot burner, and a movable stop adapted to cooperate with said valve stem for initially holding said valve in

30 open position, a temperature responsive mechanism associated with said pilot burner, another stop positioned adjacent said valve stem and cooperating with said temperature responsive mechanism, said temperature responsive mechanism being cooperatively associated with said second mentioned stop for moving said stop into abutting relationship with said valve stem and displacing said first mentioned stop therefrom.

35 11. The combination with a fluid burner, of a longitudinal stem valve for controlling the flow of fluid thereto, an arm member and a lever member pivoted adjacent said valve

40 stem, resilient means normally pressing said arm and lever members into abutting relationship with respect to each other and biasing said arm member to hold said valve in "initial" open position in response to movement of said valve to such position, said lever member having a lug portion at one end thereof, a temperature responsive mechanism cooperating with the lug portion of said lever member for modifying the effect of said resilient means, and operable to displace said arm member from valve holding position, and to place said lever member in valve holding position.

45 12. The combination with a fluid burner of a longitudinal stem valve for controlling the flow of fluid thereto, a plurality of levers disposed adjacent the end of said valve stem, each of said levers having a face formed for abutment with the end of said valve stem, means for normally holding said levers in

abutting relationship with respect to each other and in a given relative relationship with respect to the end of said valve stem, so that one of said levers will normally abut against the valve stem, and additional means cooperating with one of said levers for changing the relative positioning of said levers with respect to said valve stem, and operable for displacing the lever abutting the valve stem from valve holding, and for placing another lever in abutting and valve holding, relationship with respect thereto.

50 13. The combination with a fluid burner of a longitudinal stem valve for controlling the flow of fluid thereto, a plurality of levers disposed adjacent the end of said valve stem, each of said levers having a face adapted to abut the same portion of the end of the valve stem, means disposed for normally maintaining said levers in abutting relationship with respect to each other and in a given relative relationship with respect to the end of said valve stem and one of said levers in abutting relationship with said stem, and a temperature responsive mechanism for changing the

55 relative positioning of said levers with respect to said valve stem and displacing the lever in abutment with said stem from valve holding position, and placing another of said levers in abutting and valve holding relationship.

60 14. The combination with a fluid burner of a longitudinal stem valve for controlling the flow of fluid thereto, a pivoted arm member having a stop portion disposed adjacent the end of said valve stem, means normally positioning said arm in a given relative position with respect to said valve stem, a lever member pivoted adjacent the end of said valve stem, said lever member having means

65 normally holding it in abutting relationship with said arm member, and means cooperating with said lever member and operating upon said positioning means for changing the relation of said arm with respect to said valve stem, said means displacing said lever from and placing said arm in valve holding position.

70 15. The combination with a fluid burner, of a valve for controlling the flow of fluid thereto, means normally biased to hold said valve in open position in response to movement of said valve to such position, a mechanism cooperating with said means for displacement thereof, and means disposed to take substantially the exact displaced position of said first mentioned means when displaced, said second mentioned means being disposed in cooperative relation with said mechanism for actuation thereby.

75 16. The combination with a fluid burner of a longitudinal stem valve for controlling the flow of fluid thereto, upper and lower lever members pivoted at a common point and disposed adjacent the end of said valve stem,

means normally holding said members in abutting relationship adjacent the end of said valve stem, one of said levers abutting against the end of said valve stem, and additional means for modifying the action of said first mentioned means for displacing one of said levers from abutting relation with respect to the end of the valve stem and placing the other lever in abutting relationship therewith, said last mentioned means including a temperature responsive mechanism.

17. The combination with a fluid burner, of a suitable longitudinal stem valve for controlling the flow of gas thereto, a plurality of pivotal levers disposed adjacent said valve stem, means normally holding said levers in abutting relationship with respect to each other and in a given relative relationship with respect to said valve stem, and holding one of said levers in abutting relationship with said stem, and additional means for changing the relative position of said abutting levers with respect to said stem, and operable for displacing said levers in abutting relationship with respect to said stem and for holding said stem in different open positions.

18. The combination with a fluid burner of a valve having a stem disposed for longitudinal movement and for controlling the flow of fluid thereto, means biasing said valve towards a closed position, members disposed adjacent said stem, means biasing adjacent edges of said members toward abutment with each other, said edges when in abutment being disposed to act as a stop for said valve and hold it open, and means disposed to separate said edges from abutment and permit said valve stem to pass therebetween and close said valve.

40 In testimony whereof, I have hereunto subscribed my name this 24th day of March, 1926.

EDWIN RUUD.
